UNITED STATES PATENT OFFICE

ARTHUR N. PLANTE, OF TORRINGTON, CONNECTICUT

SCREW DRIVER

Application filed November 12, 1928. Serial No. 318,705.

This invention relates to screw drivers and particularly to a tool of this character provided with a member or members having two or more screw engaging bits available for use at different angles relative to the longitudinal extent of the tool. In the numerous structures where screws are employed to secure parts together it frequently happens that while certain of the screw heads are directly accessible for engagement therewith of a straight screw driver applied in the direction of the longitudinal axis of said tool, other screw heads may be inaccessible for rotation in this manner due to overlying or adjacent parts and may be conveniently actuated only by means of a screw bit angularly extended from its supporting shank. In certain cases it may be desirable that the extent of such a bit in the direction of its width be substantially coincident or parallel with a plane defined by the screw driver shaft and in other cases it may be desirable that the extent of such a bit be in transverse relation to such a plane. The object of my invention is the provision in a screw driver of an adjustable blade or blades having several bits available for application to screw heads respectively from various desirable angles. To this end my invention consists in the arrangement of elements disclosed in the forms of embodiment of my invention illustrated in the accompanying drawings.

In the drawings,

Figure 1, is a view of a screw driver handle and shank with the latter supporting an adjustable blade provided with bits extended at different angles.

Figure 2, is a sectional view on line 2—2 of Fig. 1.

Figure 3, is a detail view of the shank and blade shown in Fig. 1, indicating an intermediate position of the blade during change thereof from one position to another.

Figure 4, is a detail view similar to Fig. 3, showing the blade in a different position from that in which it is shown in Figs. 1 and 2.

Figure 5, is a side view of a screw driver having a shank of a form different from that

shown in Figs. 1 and 2 said shank supporting two blade elements instead of one.

Figure 6, is a view of the blade carrying end of the tool shank shown in Fig. 5, as it would appear viewed from below in said figure, but with the blade elements shifted from a normal position to one where one of the elements is operable for axial or angular adjustment.

Figure 7, is a sectional view on line 7—7 of Fig. 6.

Figure 8, is a view similar to Fig. 6, showing one of the blade elements in a normal position different from that in which it is shown in Fig. 5.

Figures 9, 11 and 10, are views similar respectively to Figs. 6, 7 and 8, but showing a different form of blade element.

Referring to the drawings the screw driver illustrated in Figs. 1, 2, 3 and 4 includes the shank 1, handle 2, and blade 3. The shank is formed of a suitable bar of stock, preferably though not necessarily square in cross section. At one end the bar is somewhat flattened as at 4, and bent upon itself to form a loop 5, having sleeved thereon a length of tubing 6, to form a hand grip. The outer end of the flattened portion 4, is fitted against a shoulder 7, of the body of the shank and firmly held thereto as by a rivet 8. The blade or tool supporting end of the shank is flattened as at 9, and provided with an elongated slot 10, the outer end of the slot being substantially concentric with the end of the shank which is preferably rounded for a purpose that will presently appear. Formed integrally with the blade 3, are the screw engaging bits 12, 13 and 14, each of which extends at a different angle relative to the main portion of the blade, that is to say the bit 12, at one end of the blade extends flatwise therewith, bit 13, at the other end of the blade extends transversely at right angles thereto, and the bit 14, at one side of the blade extends lengthwise thereof and at right angles thereto.

The shank and blade are assembled in flatwise relation to each other and may be held together by means of a stud or bolt 15, fitted as shown to a hole in the blade and extend-

ing through the elongated slot in the shank. It will be apparent that this arrangement may be reversed, that is, the elongated slot may be made in the blade and the hole in the shank. When the blade and shank are associated as shown, the blade together with the stud is movable longitudinally of the shank within limits defined by the slot. With the stud at the rear of the slot, the laterally extended bit 14, engages the side of the shank and serves to hold the blade rigid therewith, see position of blade shown in Fig. 1, with bit 13 in position for use. To reverse this position of the blade and bring bit 12 into position for use, the blade together with the stud is moved longitudinally of the shank to place the stud at the forward end of the slot and concentric with the end of the shank so that the blade may be turned about the axis of the stud and then moved backward to locking position again, that is with the stud at the rear of the slot and with bit 14, serving as a locking flange against the shank, same as shown in Fig. 1, but with the bit 25 14, against the opposite side of the shank. The bit 14, is in position for use in either of the described positions of the blade.

Referring to Figs. 5, 6, 7, 8, 9, 10 and 11, the numeral 21, designates a type of screw 30 driver shank with which may be assembled to embody my invention the various forms of bit elements presently to be described. This form of shank may consist of a strip of metal bent upon itself and provided with a rubber 35 hose handle sleeved upon the intermediate portion of the strip as shown in Fig. 5. The resulting form of handle may be defined as having a bifurcated shank which, although not essential to my invention has been found 40 to be well adapted for my purpose.

In the form of my invention shown in Figs. 5, 6, 7 and 8, blade elements secured between the shank furcations 22 and 23, are designated by 24 and 25, respectively. A rivet 26, extends through both elements or blades and through slots 27 and 28, in the respective furcations 22 and 23. As shown in Fig. 5, the element 24, is flanged at both sides 29 and 30, to engage furcation 22, and presents a bit 50 31, extended at the extreme end of the tool and at right angles to the longitudinal axis of the screw driver shank.

The blade 25, is flanged on one side as at 32, to engage furcation 23, and presents two 55 bits 33 and 34, extending respectively in substantial alignment with the longitudinal axis of the shank and at right angles thereto in a plane at right angles to that of bit 31. As shown in Fig. 5, the bits 31 and 33, are in position for use, the assembled blades 24 and 60 25, together with rivet 26, having been slipped back from the position in which they are shown in Fig. 6. The blades 24 and 25, together with rivet 26, are permitted to move longitudinally of the shank to either the po-

sition shown in Figs. 5 and 8, or to the position shown in Fig. 6, by virtue of the elongated slots 27 and 28. In either position blade 24 is prevented from rotative movement about the rivet axis by the side flanges 70 29 and 30, which engage furcation 22, and in the position shown in Figs. 5, and 8, blade 25 is prevented from similar movement by the side flange 32, which engages furcation 23. In the position of the blades shown in Fig. 6, however, blade 25 is rotatable from the position there shown an amount which brings flange 32, in alignment with the opposite side of furcation 23, and in the two extreme positions of the blade 25 thus defined, 80 it may be immovably locked to the shank by a longitudinal movement therebetween, permitted by the elongated slots 27 and 28. In one position bit 33, is available for use and in the other position bit 34, is available for 85 use.

In the form of my invention shown in Figs. 9, 10 and 11, a single blade 40, is shown which is provided with three bits 41, 42, and 43, and a side flange 44. Movement of this blade 90 longitudinally of the shank to its forward position permits the blade to be turned as desired about its pivotal rivet 45. The blade may then be locked in the desired position by moving it to its backward position.

Having thus described my invention, what I claim is,

1. A tool of the class described including in combination a shank, a blade having an angularly extended bit, and a stud for associating the blade with the shank, said stud being fixed in one member and movable in a slot in the other member whereby when the stud is at the outer end of the slot the blade is free to partially rotate about the axis of the stud 100 and when the stud is at the inner end of the slot the blade is locked to the shank by engagement therewith of the angularly extended bit.

2. A tool of the class described including in combination, a shank and a blade, one of said members having an angularly extended flange, and a stud for associating the blade with the shank, said stud being fixed in one member and movable in a slot in the other member whereby when the stud is at one end of the slot the member to which the stud is fixed is free to partially rotate about the axis of the stud and when the stud is at the other end of the slot the said members are locked together by engagement of one with the flange of the other.

3. A tool of the class described including in combination a bifurcated shank, a blade having an angularly extended bit, and a stud for associating the blade with the shank, said stud being fixed in one member and movable in a slot or slots in the other member whereby when the stud is at one end of the slot or slots the blade is free to partially rotate about 125 130

the axis of the stud and when the stud is at the other end of the slot or slots the blade is locked to the shank by engagement therewith of the angularly extended bit.

5 4. A tool of the class described including in combination, a shank, a blade comprising a flat body portion having a bit extended therefrom in the plane of the body of the blade, and a pair of bits extended substantially at right angles to said plane of the body of the blade respectively in opposite directions therefrom and in respective planes substantially at right angles to each other, and a stud for associating the blade with the
10 shank, said stud being fixed in one member and movable in a slot in the other member whereby when the stud is at one end of the slot the blade is free to partially rotate about the axis of the stud and when the stud is at
15 the other end of the slot the blade is locked to the shank by engagement therewith of one of the angularly extended bits.
20

In testimony whereof I affix my signature.
ARTHUR N. PLANTE.
